DESIGN FOR A PACKING AND CARRYING RECEPTACLE

Mack J. McKee, Dallas, Tex., assignor to The Figaro Company, Inc., Dallas, Tex., a corporation of Arizona

Application December 22, 1945, Serial No. 124,955

Term of patent 7 years

(Cl. D58—4)

To all whom it may concern:

Be it known that I, Mack J. McKee, a citizen of the United States of America, residing at Dallas, in the county of Dallas and State of Texas, have invented a new, original, and ornamental Design for a Packing and Carrying Receptacle, of which the following is a specification, reference being had to the accompanying drawing, forming a part thereof.

Fig. 1 is a perspective view of a packing and carrying receptacle showing my new design,

Fig. 2 is a plan view showing the top, front and base ledge, and

Fig. 3 is an elevation of the end opposite from that shown in Fig. 1.

The essential features of my design reside in the surface ornamentation shown on the front and two sides of the box, the back of the box being plain.

I claim:

The ornamental design for a packing and carrying receptacle, as shown and described.

MACK J. MCKEE.
